METHOD AND MEANS OF GARMENT
SUSPENSION

Sylvan Eisenberg, Belmont, Calif.

Application November 29, 1948, Serial No. 62,533

2 Claims. (Cl. 223—96)

1

This invention relates to a new and useful improvement in a hanger for skirts, trousers, and the like, and more particularly to a method wherein a slideable spring is used to provide tension on the gripping members of the hanger from which garments may be suspended.

Heretofore, it has been customary to clamp garments tightly in such hangers by using a horizontal member slideable vertically along the hook of the hanger, several notches on the hook, in some instances providing the means for holding the sliding member in the adjusted position. Thus, the rigid and tightly adjusted member exerts sufficient tension on the hook to clamp or hold the garment between the gripping members or slabs.

This practice of the prior art possesses the disadvantage that the two arms of the hook which support the gripping members through constant tightening of the said sliding member in the notches, bends the hook arms out of shape. Depending upon the frequency with which such hangers are used, this bending action of the hook arms sooner or later causes a permanent set or distortion and loss of elasticity in the arms of the hook, with the result that the sliding member can no longer be tightened. When this occurs the hanger loses its usefulness, since a garment cannot be held in place any longer.

An important object of this invention is to prevent permanent set or distortion of the arms of the hook of a clamp type garment hanger by using a horizontal spring slideable vertically on the hook arms in such a manner as to clamp the gripping members or slabs tightly together by resilient action, thus relieving the hook of pressure and assuring the hanger of increased durability and useful life.

A further object of this invention is to provide an exchangeable spring which, by removal and replacement from time to time, will extend the serviceability of the hanger to almost unlimited duration.

An additional object of this invention is to provide a means of simple construction which will permit improvement of existing hangers by the use of a spring as described herein.

Further objects are to provide a construction of maximum simplicity, economy and ease of assembly and disassembly, and such further objects, advantages and capabilities as will fully appear and as are inherently possessed by the device and invention described herein.

The invention further resides in the combination, construction and arrangement of parts 11-

2

illustrated in the accompanying drawings, and while there is shown therein a preferred embodiment and one variant thereof, it is to be understood that the same are merely illustrative of the invention and that the invention is capable of modification and change and comprehends other details of construction without departing from the spirit thereof or the scope of the appended claims.

10 Referring to the drawings:

Figure 1 is a side elevation of a hanger embodying the present invention.

Figure 2 is a perspective view of the same, showing an adjustment of the tensioning member.

Figure 3 is a perspective view of a hanger embodying the instant invention, showing a modified type of spring tensioning member adapted to accomplish the objects and results set forth herein.

Figure 4 is a fragmentary sectional view taken along the line IV—IV of Figure 1.

Figure 5 is a sectional view to an enlarged scale taken along the line V—V of Figure 3.

25 In the drawings, in which like reference numerals indicate like parts in the several views, and which represent for the purposes of illustration a preferred embodiment of the invention, there is shown at 15 two slabs or gripping

30 members formed of metal, wood, plastic, or other suitable material. A hook 16 made of metal or other suitable material having resilient characteristics, has two arms 14 which are attached at the free ends thereof to the central portion 35 of each slab 15, although attachment may be at any point for specialized purposes. By pulling the two arms 14 of the hook 16 together, the slabs 15 are closed in such a manner as to hold a garment 18 firmly in place therebetween. A tension spring 17 has its ends slideably supported on the arms 14 of the hook 16 in such a manner that when the spring is moved upwards along the arms of the hook 16 the resilient action of the hook opens the gripping member 15 conveniently,

40 and when the spring 17 is moved downwardly along the arms 14 of the hook 16 the spring closes the slabs 15 by exerting overpowering tension on the arms of the hook.

45 A torsion spring 19 of the type illustrated in Figure 5 may be substituted for the tension spring 17, if desired, without departing from the scope of the instant invention.

When the hanger is empty and the spring 17 is raised to its uppermost position neither of the arms 14 of the hook 16 or the spring 17 is under

tension. As a garment 18 is clamped between the gripping member 15, the spring 17 is moved downward, sliding along the arms 14 of the hook 16. Although the spring 17 is normally prevented by the thickness of the garment 18 from completing closing the clamping members 15, downward movement of the spring 17 is stopped as soon as the spring 17 exerts sufficient tension to hold the gripping members 15 in predetermined pressing engagement with the garment 18. Thus, the spring 17 serves to absorb the tension necessary to clamp the slabs 15 towards one another.

In order to release the garment 18, spring 17 is moved upwards by sliding it along the arms 14 of the hook 16 until the gripping action of the members 15 is eased sufficiently to permit the garment 18 clamped therebetween to be readily and easily removed.

From this description it will be apparent that the present invention produces a method of quickly and easily gripping and releasing garments from a hanger. Any hanger which is constructed along the lines indicated may readily be modified to embody the present invention by providing such a hanger with a spring of the type disclosed herein.

I claim:

1. A garment hanger of the character described, comprising co-operable jaws for gripping a skirt or the like, a suspension element and handle in the form of a continuous length of resilient wire or rod bent into a generally U-shape having a base and generally parallel legs, said element being bent adjacent its base to form a hook, being also bent adjacent its opposite end and fixed at said end to said jaws, said suspension element acting to urge said jaws to open

30

35

position, and a spring slidably attached at its opposite ends to said legs, extending therebetween and slidably therealong to exert a resilient closing force on said legs which diminishes as said spring means is moved along said legs away from said jaws.

2. A garment hanger of the character described, comprising co-operable jaws for gripping a skirt or the like, a suspension element and handle in the form of a continuous length of resilient wire or rod bent into a generally U-shape having a base and generally parallel legs, said element being bent adjacent its base to form a hook, being also bent adjacent its opposite end and fixed at said end to said jaws, said suspension element acting to urge said jaws to open position, and a coil spring having its end portions encircling said legs and slidably therealong, said spring being of a length to be under tension throughout a substantial range of its movement along said legs and cooperating with the legs of said suspension element to exert increased resilient closing force as said spring is moved toward said jaws.
